UNITED STATES PATENT OFFICE.

AUGUST H. LORENZ, OF CHICAGO, ILLINOIS, ASSIGNOR, BY MESNE ASSIGNMENTS, TO ARTHUR W. FRISKEY, OF CHICAGO, ILLINOIS.

LOOSE-LEAF BINDER-FRAME.

SPECIFICATION forming part of Letters Patent No. 754,324, dated March 8, 1904.

Application filed August 4, 1902. Serial No. 118,297. (No model.)

To all whom it may concern:

Be it known that I, AUGUST H. LORENZ, a citizen of the United States, residing at Chicago, in the county of Cook and State of Illinois, have invented certain new and useful Improvements in Loose-Leaf Binder-Frames, of which the following is a specification.

This invention relates to novel improvements in loose-leaf binder-frames, and has for its object to simplify and improve the construction of frames of this character and at the same time lessen the cost of manufacture.

With these and other objects in view the invention contemplates a frame in three sections, a back section and two corresponding cover-sections which are connected by crossed levers having their ends suitably guided in the cover-sections, and a single screw connected with one of the sections and with said levers at the point where they cross each other, whereby both of the cover-sections may be adjusted relative to the back section in the same manner and to a corresponding degree by manipulating the single screw.

I have illustrated one form in which my invention may be embodied in the accompanying drawings, in which—

Figure 1 shows the inside of a frame containing the invention with the covers extended and partly broken away. Figs. 2 and 3 are transverse sectional views on the lines 2 2 and 3 3, respectively, of Fig. 1.

In the drawings like numerals of reference indicate corresponding parts in the several figures, and referring thereto 10 designates the back section, and 11 12 the two cover-sections, which together constitute the principal parts of the frame. In the construction shown in the drawings the cover-sections are of angular shape and are each provided with inwardly-extending ends 13, which are arranged to slide inside of the ends 14 on the back section. The back section is shown provided with a longitudinal central rib 15, and a guide-plate 16 is removably fastened to this rib at each end thereof and projects on either side of the rib to form a guide for the cover-sections, the end of said cover-sections being

held snugly between these guides and the ends of the back section.

The two cover-sections are fastened to the back section and maintained in corresponding relation thereto by a pair of levers 17, which cross each other at their middle and are provided at their ends with pins 18, which are arranged to ride in longitudinal grooves 19 in the cover-sections. The crossed levers 17 are secured to the back section by means of a bolt 20, which is screwed into an opening in the back and is provided with a shoulder 21 to bear against the crossed levers and hold them in place. This bolt is provided with an enlarged head 22, and a screw-bolt 23 is arranged in a transverse threaded opening 24 in said head and extends through the side of one of the cover-sections. The head 25 of the bolt is adapted to receive a key, and a washer 26 and pin 27 secure the bolt in the recessed offset section 28 of the cover-section. The head of the bolt is countersunk in the cover-section, so that the outer face of said section may present a smooth and unobstructed surface.

I provide four leaf-rests, each of which comprises a tube 30, fastened to one cover-section, and a rod 31, fastened to the other cover-section and operating in the tube. These leaf-rests are preferably arranged with the tubes and rods on each cover-section alternating with each other.

The covers 32 may be connected with the cover-sections in any suitable manner, as by pivot-pins 33 passing through the lugs 34.

It will thus be observed that I employ only a single screw extending through the side of the frame for adjusting the cover-sections and that these cover-sections are secured together and to the back section by means of the crossed levers, which maintain the cover-sections in positive and fixed relation to each other and to the back section and which are caused to operate by turning the screw to adjust the cover-sections in absolute correspondence to each other. The crossed levers also hold the cover-sections in constant proper alignment with each other and with the back

section and prevent binding at either end of the frame. While I prefer to employ the guide-plates at each end of the back section, it is apparent that these guides are not absolutely necessary, because the crossed levers will hold the sections in proper relation.

As my improved binder-frame comprises only a very few parts and as the construction and operation is very simple, it is apparent that it can be manufactured inexpensively without detracting from its strength or usefulness. I may make the frame by stamping the sections out of sheet metal or by casting them, or, if desired, each section may be built up of plates properly formed and fastened together.

The binder-frame may be made in any desired size, and it will be observed that pressure can be supplied by adjusting the screw-bolt to clamp the cover-section on the leaves as tightly as required to hold them rigidly and securely in place.

My improved binder-frame is free from complicated parts and does not require any degree of special skill for operating.

I am aware that my invention may be embodied in many different forms which will differ from each other and from that herein shown and described in the details of construction and arrangement of parts, and it will be understood that I reserve the right to make all such changes as fairly fall within the spirit and scope of the invention.

I do not limit the invention to the use of leaf-rests of any particular number or construction; nor do I limit myself to any particular manner of connecting the covers with the frame, as various means may be employed for this purpose without departing from the invention.

It will of course be understood that the sections are intended to be covered with leather, cloth, or other suitable material and that the back section, which carries the inscription, is always held intermediate of the covers by reason of the fact that both cover-sections are adjusted simultaneously and to a corresponding degree.

Having thus fully described my invention, what I claim, and desire to secure by Letters Patent, is—

1. A loose-leaf binder-frame comprising a back section and two cover-sections, crossed levers connecting said cover-sections, and a screw arranged transversely in the frame and adapted to be operated to adjust the cover-sections simultaneously.

2. A loose-leaf binder-frame comprising a back section and two cover-sections, one pair of levers connected at their ends to said cover-sections and crossed at or about the middle of the frame, and a screw-bolt connected with said crossed levers and operating transversely

through one cover-section for simultaneously adjusting said cover-sections. 65

3. A loose-leaf binder-frame comprising a back section and two cover-sections, and a screw-bolt connected with the back section and operating transversely through one cover-section for simultaneously adjusting both 70 cover-sections.

4. A loose-leaf binder-frame comprising a back section and two cover-sections, crossed levers connected at their ends to said cover-sections, and a screw-bolt arranged transversely in the frame and having a bearing against one cover-section and connected with said crossed levers to adjust both cover-sections simultaneously. 75

5. A loose-leaf binder-frame comprising a back section and two cover-sections, levers connected at their ends to said cover-sections and crossed at or about the middle of the frame, and a transversely-arranged screw-bolt connected with said levers at the point where 85 they cross each other.

6. A loose-leaf binder-frame comprising a back section and two cover-sections, crossed levers connected at their ends to the cover-sections and at their middle with the back section, and a screw-bolt connected to said levers at or about their middle and having a bearing 90 against one of said sections.

7. A loose-leaf binder-frame comprising a back section and two cover-sections, said cover-sections being provided with guide-grooves, a pair of crossed levers connected at their middle to the back section, pins on the ends of said levers arranged to travel in said grooves, and a screw-bolt operating through one of the 100 cover-sections and connected with the crossed levers and adapted to be operated to adjust said cover-sections simultaneously. 95

8. A loose-leaf binder-frame comprising a back section and two cover-sections, levers 105 crossed at or about their middle and connected at their ends to the cover-sections, a bolt securing said levers at the point where they cross to the back section and provided with a transverse opening in its head, and a screw-bolt 110 operating in said opening and through one of the cover-sections.

9. A loose-leaf binder-frame comprising a back section and two cover-sections, connecting means for said cover-sections, a member 115 carried by said back section and provided with a transverse threaded bolt opening therein, and a screw-bolt operating through and bearing against one cover-section and working in said threaded opening.

10. A loose-leaf binder-frame comprising a back section and two cover-sections, levers connected at their ends to said cover-sections and crossing each other at or about the middle of the frame, a bolt passing through said 125 levers where they cross and secured to the

back section, said bolt being provided with a transverse threaded opening in its head, and a screw-bolt passing transversely through and bearing against one of the cover-sections and working in said threaded opening.

11. In a binder-frame, the combination of a binding means comprising two parts, one of which is movable with relation to the other, a back member, a lever having its ends operatively connected with said parts respectively, a fulcrum for said lever mounted in said back member, and means for oscillating said lever upon said fulcrum.

12. In a binder-frame, the combination of a binding means comprising two relatively movable members, a back member, a pair of crossed pivoted levers having their ends operatively connected with said members respectively, and means secured to said back member for moving said levers relatively.

13. In a binder-frame, the combination of a binding means comprising two relatively movable members, a back member, crossed levers pivoted to said back member and having their ends operatively connected with said first members, and means for oscillating said levers upon their pivot. 25

14. In a binder-frame, the combination of a binding means comprising two relatively movable members, a back member, crossed levers pivoted to said back member and having their ends operatively connected with said first two members, and means secured to said back member for oscillating said levers upon their pivot. 30
